H. B. MINNICK

GAME

Filed May 3, 1922

Eng-1

Technical drawing of a circular component, likely a dial or gauge face. The drawing includes the following labels and features:

- Outer ring: **16** at the bottom, **14** on the right, **17** on the left, and **16** at the top.
- Inner circle: **100** at the center.
- Major markings: **11** at the top right, **15** at the top left, **17** at the bottom left, and **17** at the bottom right.
- Minor markings: **20** at the top left, **50** at the bottom left, and **50** at the bottom right.
- Small circles: **ZERO** at the top left, **ZERO** at the bottom left, and **ZERO** at the bottom right.
- Arrows: **→ 5** at the top right, **→ 5** at the bottom right, and **→ 5** at the bottom left.
- Other labels: **13a** and **13b** pointing to rectangular cutouts at the top, and **16** at the bottom left.

INVENTOR

UNITED STATES PATENT OFFICE.

HOWARD B. MINNICK, OF CHICAGO, ILLINOIS.

GAME.

Application filed May 3, 1922. Serial No. 558,149.

To all whom it may concern:

Be it known that I, HOWARD B. MINNICK, a citizen of the United States, residing at Chicago, in the county of Cook and State 5 of Illinois, have invented a certain new and useful Improvement in Games, of which the following is a specification.

The object of my invention is to provide an amusing, interesting and quasi-educational, game requiring a degree of skill to secure the most satisfactory results to the player.

A further object is to provide such a game, and rules governing the same, that it 15 may partake of the nature of a competitive play between those engaging in it, the play not being limited to any certain number of people.

A further object is to provide such a 20 construction for my device that it will be strong, durable, and inexpensive to produce, and it will be easily operated and understood.

My invention consists primarily in a plate 25 provided with a number of recesses adapted to receive, and retain when placed therein, movable and erratically moving objects, the recesses being numbered to denote a certain number which is to be added or subtracted, 30 as the case may be, from the player's total score when the object comes to rest in its recess. The plate is preferably provided with upwardly extending flanges on all of its sides so as to keep the moving objects 35 from rolling off the plate. A preferable construction is to have these sides extend upwardly in box form, and to place a transparent material over the top, thereby completely closing the moving objects within a 40 box, the base of which constitutes the plate referred to.

In the drawings I have illustrated a preferable construction for my device, in which

Fig. 1 shows a plan view.

Fig. 2 shows a longitudinal sectional view.

Fig. 3 shows preferable construction of the movable objects, the plates thereof being separated, but in juxtaposition.

Fig. 4 shows a detailed view of a modified form of my device.

Fig. 5 is a sectional view taken on the line 5—5 in Fig. 4.

Referring to the accompanying drawing, 55 reference numeral 10 is used to indicate the plate (which, in the drawing is shown as the

base of the box), and the numerals 11 indicate the recesses designed to receive the movable objects. The numeral 13 indicates the objects which are preferably constructed of two telescoped mating capsule members, 13^a and 13^b, with a weight 14 (preferably a round lead-like weight, like a piece of shot) enclosed within the two members forming the capsule.

The numerals 15 indicate the upwardly extending sides of the plate, and the numeral 16 indicates the transparent material (preferably glass) which forms a top which is secured on top of the flanges, the whole 70 of the plate, sides and top forming a box-like arrangement with a transparent top.

As above indicated, the recesses are numbered as desired, and for symmetry and pleasing appearance, these are arranged circumferentially around a center, the plate being painted with stripes circling the center, similar to a bull's eye on a target.

In my modified form (Fig. 4), I show 80 hazards 17, which may be placed in close proximity to the recesses, to thereby make it more difficult for the operator to seat a capsule within a particular recess.

The rules governing the game to be 85 played are preferably that when one of the plurality of moving objects become seated in a zero recess, that the total number of the score obtained from the addition of the numbers accompanying the recesses in which the other objects seat themselves shall 90 be deducted from the total score of the player. If the player is sufficiently fortunate that by tilting or tipping the plate, he can seat the objects only in recesses which have numerals other than zero, then this total is to be added to the score of the player. The total score constituting a game, may be placed at any desired figure, and when one 95 of the players, in his turn, attains that score, he has won the game.

I am aware that games similar to this are in existence, and that some of the same have been patented, but in all such that I have observed, there has never been the utilization of a plate of this kind with recesses, some of which are numbered and some of which have a zero indication, used for the purpose of constituting a game, or for any other purpose.

Various changes may be made in my device without altering the spirit of my invention, and I do not desire to be understood as

limiting this application, other than is set forth in the appended claim.

Having thus described my invention, what I claim and desire to secure by Letters Patent of the United States, is:

A game comprising a receptacle and a transparent cover therefor; a plate positioned in the base of the receptacle and provided with a plurality of recesses to receive and temporarily retain movable ob-

jects, said recesses bearing certain numbers or zero characters; being arranged circumferentially around a center, said plate being painted with stripes similar to the bull's eye on a target hazards on the plate 15 positioned in close proximity to their respective recesses; movable objects to be seated in the recesses, substantially as and for the purposes set forth.

HOWARD B. MINNICK.
